UNITED STATES PATENT OFFICE.

WILLIAM MAINE TREGLOWN, SR., OF NEW YORK, N. Y.

WRENCH.

SPECIFICATION forming part of Letters Patent No. 701,108, dated May 27, 1902.

Application filed September 28, 1901. Serial No. 76,879. (No model.)

To all whom it may concern:

Be it known that I, WILLIAM MAINE TREGLOWN, Sr., a citizen of the United States, and a resident of the city of New York, (Richmond Hill, borough of Queens,) in the county of Queens and State of New York, have invented a new and Improved Wrench, of which the following is a full, clear, and exact description.

10 The improvement relates to pipe-wrenches; and its object is to provide a new and improved wrench which is simple and durable in construction and arranged to permit of quick and convenient adjustment for gripping large and small articles and turning the same in either direction.

The invention consists of novel features and parts and combinations of the same, as will be fully described hereinafter and then 20 pointed out in the claims.

A practical embodiment of the invention is represented in the accompanying drawings, forming a part of this specification, in which similar characters of reference indicate corresponding parts in all the views.

Figure 1 is a side elevation of the improvement as applied for turning and unscrewing a pipe. Fig. 2 is a like view of the same with parts in section and the jaws arranged to engage a round article for turning and screwing of the same, and Fig. 3 is an inverted sectional plan view of the improvement on the line 3 3 of Fig. 1.

The wrench consists, essentially, of a fixed 35 jaw A, having an integral handle B, adapted to be taken hold of by the operator for manipulating the wrench, and of a hook-jaw C, having a pivot D engaging spaced angular slots E and E', connected with each other by a slot E² and terminating in upturned ends E³ E² and E⁵ E⁶, respectively. The jaw A has its edge provided with segmental gripping-faces A' A², extending at angles one to the other and preferably serrated, and the hook-jaw C has its inner edge curved and likewise serrated to form a gripping-face C', working in conjunction with either of the gripping-faces A' A², according to the size of the article to be gripped and to the direction in which 45 the gripped article is to be turned.

By the arrangement described the hook-

jaw C can be readily adjusted by moving the jaw and with it its pivot D until the latter engages any one of the upturned ends E², E³, E⁴, or E⁵, which form adjustable fulcrums for 55 the hook-jaw C. It will be seen that the gripping-face of the hook-jaw C can be brought into any desired relation to either of the gripping-faces A' A² of the handle-jaw A for gripping larger and smaller objects and for turning the same either forward or backward, as the case may require. The invention is not limited to the actual form of the jaws and the slots described, as it is obvious that the features may be modified without departing 60 from the spirit of the invention. The pivotal end of the jaw C is preferably forked to straddle the handle-jaw A, it being understood that the pivot D engages both members of the fork and when removed permits a ready 65 disconnection of the hook-jaw from the handle-jaw A.

Having thus described my invention, I claim as new and desire to secure by Letters Patent—

75 1. A wrench, comprising a fixed jaw having gripping-surfaces on its opposing edges and provided with a slot having a plurality of bearings, and a movable hook-jaw having a pivot working in the slot of the fixed jaw 80 and adapted to be seated in said bearings, as and for the purpose set forth.

2. A wrench comprising a handled jaw having segmental gripping-surfaces and provided with a plurality of connected angular slots, 85 and a hook-jaw having a pivot for engaging the said slots to change the fulcrum of the hook-jaw on the handled jaw to permit it to work in conjunction with either gripping-surface of the handled jaw, as set forth. 90

3. A wrench comprising a handled jaw having gripping-faces standing at angles one to the other, the said jaw also having angular slots arranged one above the other and a slot connecting the angular slots, and a hook-jaw 95 having a pivot for engaging the said slots, to allow of changing the hook-jaw relative to the said gripping-faces of the handled jaw, as set forth.

4. A wrench comprising a handled jaw having spaced side slots terminating in angular ends and a connecting-slot for connecting the

said side slots with each other, and a hook-jaw having a pivot for engaging the said slots, as set forth.

5. A wrench, comprising a handled jaw having gripping-surfaces on its opposing edges and provided with an angular slot, the ends of which are upturned to form bearings, and a hook-jaw, forked to straddle the handle-jaw and provided with a pivot connecting the

members of the fork and working in the slot 10 of the handled jaw, as set forth.

In testimony whereof I have signed my name to this specification in the presence of two subscribing witnesses.

WILLIAM MAINE TREGLOWN, Sr.
